CLAIM

The ornamental design for a dispensing spout, as shown and described.

DESCRIPTION

FIG. 1 is a front perspective view of a dispensing spout showing my new design;

FIG. 2 is a rear perspective view thereof;

FIG. 3 is a right view of the dispensing spout, the left view being a mirror image;

FIG. 4 is a top view of the dispensing spout; and,

FIG. 5 is a bottom view of the dispensing spout.

The broken lines are for illustrative purposes only and do not form part of the claimed design.
